UNITED STATES PATENT OFFICE

ALFRED MOORHOUSE, OF DETROIT, MICHIGAN, ASSIGNOR TO PACKARD MOTOR CAR COMPANY, OF DETROIT, MICHIGAN, A CORPORATION OF MICHIGAN

INTERNAL-COMBUSTION ENGINE

Application filed September 19, 1924. Serial No. 738,684.

This invention relates to internal combustion engines, and particularly to means for continuously collecting, during the operation of the engine, any lubricating oil and 5 unburned fuel that tends to pass the piston rings, and for continuously separating this oil and fuel, the oil being returned to the oil reservoir and the fuel being returned, in a vaporized state, to the combustion 10 spaces.

Due to the low grades of fuels that are frequently used in internal combustion engines, incomplete combustion results and this is particularly true when the engine is 15 cold. The unburned fuel passes downwardly around the pistons and piston rings into the lubricant in the oil supply reservoir, carrying with it impurities such as water. The resulting mixture of oil, fuel, and water 20 is very inefficient as a lubricant and it becomes necessary to frequently drain the oil reservoir and supply a fresh quantity of lubricant.

Another difficulty that arises in the operation of internal combustion engines is due 25 to the fact that the lubricating oil that is splashed up onto the pistons, to lubricate the cylinder walls, passes upwardly by the piston rings and enters the combustion 30 spaces where it is burned. This is particularly true when the pistons, rings, or cylinders become worn, and this results in a large amount of carbon being deposited in the combustion spaces, with the well known 35 objectionable results.

Devices have heretofore been provided for preventing dilution of the lubricating oil, for preventing the passage of lubricating oil upwardly around the pistons into the 40 combustion spaces, and for continuously collecting and separating the oil and fuel that tend to pass the piston rings, but they have been objectionable and inefficient in operation due to the fact that the heating retort 45 employed has been mounted as a unit with the collecting or float chamber which has resulted in the valve mechanism of said chamber being subjected to the high heat of the retort which heat in time impairs the operation of the valve mechanism. Fur-

ther, these devices occupy such a large amount of space that it is impossible to use the engine in both a right or left hand drive chassis without rearranging the parts. In addition, due to their insecure mounting, 55 leaky joints and consequent faulty operation have resulted.

An object of the present invention is to provide a dilution eliminator comprising a heating or vaporizing retort and an independently mounted collecting or float chamber that is positioned at such a distance from the retort that the valve mechanism of the float chamber will be shielded from the heat of the retort. Another object of the invention is to provide a device of this character 60 that is so constructed and mounted on the engine that the latter may be installed in either a right or a left hand drive chassis.

Further objects of the invention are to 70 provide means for independently mounting the vaporizing retort and the float chamber in such a manner that these elements will not become defective in operation because of leaky joints; to provide a device that is 75 readily accessible for repair or replacement, and one which will permit access to the other parts of the engine; and to provide means whereby the volatilized impurities in the lubricating oil, such as water, fuel and the like, 80 are returned to the intake manifold to augment the explosive mixture delivered by the carburetor.

Other objects and advantages of the invention will appear from the following description taken in connection with the drawings, which form a part of this specification, and in which,

Fig. 1 is a side elevation of an internal combustion engine embodying the present 90 invention;

Fig. 2 is a sectional end view somewhat enlarged, on line 2-2 of Fig. 3;

Fig. 3 is a top plan view, partly in section, illustrating the present invention; and 95

Fig. 4 is a detailed sectional view taken on the line 4-4 of Fig. 3.

larly to Fig. 1 which illustrates an eight-cylinder internal combustion engine; 1 is a carburetor, 2 is a fuel supply reservoir, and 3 is a vacuum tank. These parts are of any well known and suitable construction. Mounted in the usual manner in the cylinders of the engine are pistons 4 provided adjacent their upper portions with piston rings 5, fitted in suitable grooves. A vertical groove 6, which extends downwardly from the lowest piston ring groove a distance of approximately one-half the length of the piston, is formed in the outer surface of each piston in a tangent plane common to all of said pistons and, when viewed from the rear of the engine, on the right hand side of the same. Forming a continuation of the side wall of each piston, and projecting downwardly from the lower end thereof directly below groove 6, is a narrow skirt or tongue 7. A small radial opening 8 (Fig. 2) is provided in each of the pistons in the plane of the lowest piston ring groove, and diametrically opposite groove 6, for a purpose to be described hereafter.

During a portion of the stroke of the pistons each of the grooves 6 is in communication with a radial passage or opening 9 extending through the side walls of the cylinder block. The outer ends of passages 9 lead into a longitudinally extending collecting pipe or manifold 10 that is secured in any suitable manner to the side of the cylinder block inwardly of the valve stems 11. Access may be had to manifold 10 by removing the valve cover plates 12.

Extending upwardly through an enlarged portion 10', (Figs. 3 and 4) of manifold 10, which enlargement is formed at any suitable point along the length of the latter, is a hollow bolt 13 provided with openings 14 in its side walls for establishing communication between collecting pipe 10 and a passage 15 formed in the cylinder block. Preferably, the upper end of bolt 13, which constitutes a short connecting duct or passage, is threaded into the lower side walls of passage 15, thus constituting a supporting member for pipe 10.

A pipe 16 is secured at its inner end to the cylinder block by a suitable connecting member 17 in a position to form a continuation of passage 15, while the outer end of pipe 16 leads into the lower portion of a heating retort or vaporizing chamber 18 that is provided interiorly with any suitable type of baffling 18'. Preferably, retort 18 is cylindrical in shape and is mounted in a bypass portion 19 of the engine exhaust manifold 20, said retort being secured in place by means of a T-coupling 21 that has threaded engagement with a reduced portion 22, projecting upwardly from, and secured to retort 18, and that bears against

the upper surface of bypass portion 19 of exhaust manifold 20.

Leading from any desired point of the engine intake manifold 23, which manifold may be of the usual or any suitable form, 70 is a pipe 24 that is connected at its after end to the forward arm of T-coupling 21. The pipe 24, as shown in Fig. 1 of the drawing, leads downwardly from the top of the retort to the intake manifold of the engine. 75 This arrangement causes the distilled vapors which condense on leaving the heat of the retort to flow on down to the engine intake instead of dropping back into the retort. Vacuum tank 3 is provided with a 80 connection to intake manifold 23 by means of a pipe 25 that is connected to the rear arm of T-coupling 21.

Positioned at a suitable distance from retort 18, but preferably on the opposite side 85 of the engine, is a float chamber 26 which, in the form shown is in communication with the retort through a conduit that may be formed in a plurality of sections. As illustrated, the first section of the conduit is 90 formed of a pipe 27 in communication at its upper end with retort 18 and secured at its lower or inner end to the engine crank case 28. The second section comprises a 95 conduit 29 that is preferably formed integrally with and extends through crank case 28, while the third section comprises a pipe 30 that is secured at its inner end to the crank case, and which has its outer portion curved to facilitate the making or 100 breaking of its connection with the upper end of float chamber 26.

The construction of the float controlled valve mechanism that is employed in chamber 26 is of any suitable and well known 105 type, and comprises a shut-off valve 31 for closing the connection between the chamber and pipe 30, an atmospheric valve 32 for venting the chamber, and the usual float 33 for controlling the operation of these valves. 110 A check valve 34 of any desired type is provided in the lower end of chamber 26 in order that a partial vacuum may be maintained in the chamber until the latter is opened to atmospheric pressure. 115

The engine bottom cover or oil reservoir 35 is preferably formed with a laterally extending portion 36 which is provided with a circular opening in its upper surface 36'. Through this opening extends the lower portion of float chamber 26, which is provided with a circular collar 26' that rests on the upper surface 36' of the bottom cover projection 36, and which is secured in position at its lower end by means of a bolt 37 that extends upwardly through the bottom of projection 36 to engage float chamber 26. One or more openings 38 are provided in the lower portion of chamber 26 for establishing communication between said cham- 120 125 130

ber and oil reservoir 35, via the projecting portion 36.

The operation of the device is as follow:—

The reciprocation of pistons 4 creates a suction that establishes a partial vacuum in intake manifold 23, and this results in a partial vacuum being established in retort 18 through the connecting pipe 24. When the pistons move to such position that grooves 6 therein, or any one of them, are in register with openings 9 in the cylinder walls, the partial vacuum in retort 18 acts through pipe 16, passage 15 and manifold 10 to withdraw from the lowest piston ring groove and groove 6 any lubricating oil therein that has been picked up by the pistons, or any unburned fuel that tends to flow downwardly past the pistons, and to collect the mixture in the vaporizing chamber 18. Openings 8 in the pistons are of sufficient size to enable the force of the partial vacuum to withdraw the liquid but sufficient air is not admitted through these openings to destroy the vacuum. As the pistons move upwardly to their extreme position of compression, or exhaust, the tongues 7 maintain the vacuum by covering or closing the inner ends of passages 9. The heat of the exhaust gases passing out through exhaust manifold 20 and through by-pass 19 heats the mixture in the retort to such a high temperature that the more volatile products, such as gasoline, water, etc., are vaporized and pass off through pipe 24 into the intake manifold 23, where they unite with and augment the explosive mixture being delivered by carbureter 1 to the combustion spaces of the engine. The less volatile and heavier lubricating oil which is now purified and which is prevented by the baffling 18' from being drawn into pipe 24, passes downwardly through connections 27, 29, and 30 into float chamber 26, the partial vacuum in the latter being substantially equal to that in retort 18 due to the check valve 34 being maintained by the suction in closed position. When the purified oil in chamber 26 collects to a predetermined level, float 33 operates to close connection 30 and vent the chamber, whereupon the oil passes through opening 38 into the oil reservoir from which it is again distributed throughout the engine. The vacuum necessary for drawing fuel from supply reservoir 2 into vacuum tank 3 is secured through the pipe connection 25, thus avoiding the necessity of tapping the carbureter or intake manifold at more than one point.

The present invention prevents the dilution of the lubricating oil and thereby preserves its lubricating qualities. Carbon deposits which are largely due to the burning of lubricating oil and which result in improper valve action together with high en-

gine temperatures, are prevented. Mileage is increased by returning the vaporized fuel to the intake manifold to augment the normal explosive mixture. Moreover, the engine may be employed, without changing the relative positions of any of the parts, in either a right-hand or left-hand drive chassis. The various elements are so mounted that vibration does not result in leaky joints and faulty operation; all parts are accessible for inspection or replacement; and the float chamber valve mechanism is not subjected to the intense heat of the exhaust manifold.

While the invention has been illustrated and described in combination with an eight cylinder engine, it is to be expressly understood that the invention is susceptible to various mechanical expressions within the limits of the appended claims. For example, the float chamber 26 may be located at any suitable point provided it is at such a distance from retort 18 as to be shielded from the heat of the exhaust gases of combustion. The vacuum pipe 24 may be led from the carbureter instead of the intake manifold, and the pipe connection between retort 18 and float chamber 26 need not be formed in sections.

What is claimed is:—

1. In combination with an internal combustion engine and an exhaust manifold therefor, a vaporizing retort secured to said manifold and surrounded by a portion of the latter, a suction connection for said retort, a float chamber positioned at a distance from said retort, means connecting said retort to said chamber, and an oil reservoir in communication with said chamber, said chamber being partially mounted within said reservoir.

2. In combination with an internal combustion engine and an exhaust manifold therefor, a vaporizing retort secured to said manifold, a suction connection for said retort, a float chamber positioned on the opposite side of the engine from said retort, means connecting said chamber and retort, and an oil reservoir having communication with said chamber.

3. In combination with an internal combustion engine and an exhaust manifold therefor, a vaporizing retort secured to said manifold for vaporizing volatiles contained in the engine lubricant, a vacuum connection for said retort, a float chamber positioned at a distance from said retort and means connecting said retort to said chamber comprising a conduit formed of a plurality of sections.

4. In combination with an internal combustion engine and an exhaust manifold therefor, a vaporizing retort secured to said manifold, a vacuum connection for said retort, a float chamber positioned at a distance

from said retort and means connecting said retort to said chamber comprising a conduit formed in a plurality of sections, one of said sections extending through the crank case 5 of the engine.

5. In combination with an internal combustion engine having grooved pistons and an exhaust manifold, a retort secured to said manifold, a float chamber positioned on 10 the opposite side of said engine, a vacuum connection for said retort, a distributing duct secured to said engine and having communication with the grooves in said pistons during a portion of the stroke of said pistons, means connecting said duct and retort 15 and means connecting said retort and float chamber.

6. In combination with an internal combustion engine having an exhaust manifold, 20 a retort secured to said manifold, a suction connection for the retort, a float chamber, an oil reservoir having communication with said chamber, the latter being supported by said reservoir, and means connecting said retort 25 and float chamber.

7. In combination with an internal combustion engine having an exhaust manifold, a retort secured to said manifold and surrounded by a portion of the latter, a vacuum 30 connection for said retort, a vacuum tank connected to said retort, a float chamber positioned at a distance from said retort, a connecting pipe leading from said retort to said float chamber and formed in sections, 35 one of said sections extending through the crank case of the engine, an oil reservoir communicating with said float chamber, and means for securing said chamber in said reservoir.

40. 8. A device of the class described comprising, in combination with an internal combustion engine, a heating retort having baffles therein, an independent collecting chamber mounted directly on the oil reservoir of said engine, a pipe connection 45 between said retort and chamber, a suction connection for the retort, means for connecting said retort to the grooves of said pistons, and an oil reservoir communicating 50 with said chamber.

55. 9. A device of the class described comprising, in combination with an internal combustion engine having grooved pistons, a heating retort secured to the exhaust manifold of said engine, an independent collecting chamber mounted directly on the oil reservoir of said engine, a pipe connection formed of a plurality of sections between 60 said retort and chamber, a suction connection for the retort, means for connecting said retort to the grooves of said pistons, and an oil reservoir communicating with said chamber.

65. 10. A device of the class described comprising in combination with an internal

combustion engine having grooved pistons, a vaporizing retort, an independent collecting chamber mounted at a lower level, a pipe connection including a plurality of sections between said retort and chamber, one of said sections being formed integrally with the crank case of the engine, a suction connection for the retort, means for connecting said retort to the grooves of said pistons, and an oil reservoir communicating with said chamber. 70 75

11. A device of the class described comprising in combination with an internal combustion engine having grooved pistons, a vaporizing retort, an independent collecting chamber mounted at a lower level, a pipe 80 formed of a plurality of sections connecting said retort and chamber, one of said sections extending through the crank case of the engine, a vacuum connection for the retort, means for connecting said retort to the grooves of said pistons, and an oil reservoir communicating with said chamber. 85

12. In combination with an internal combustion engine, a heating retort secured to 90 the exhaust manifold of said engine and heated thereby, suction means for introducing the lubricant of the engine into said retort and removing the volatilized diluents therefrom, a collecting chamber mounted at 95 a distance from said retort, means for conducting the purified lubricant from said retort to said chamber, and means for conducting the lubricant from the collecting chamber back to the engine lubricating system. 100

13. In combination with an internal combustion engine, a vaporizing retort for purifying the used lubricant of the engine, suction means for introducing said lubricant 105 into said retort, and for returning the vapors separated from the lubricant in the retort directly to the engine fuel supply, a collecting chamber mounted at a distance from said retort, means for conducting the purified lubricant from the retort to the chamber, and means for conducting the lubricant collected in said chamber to the engine oil reservoir. 110

14. In combination with an internal combustion engine, an exhaust manifold having a by-pass portion, a vaporizing retort secured to said manifold and encircled by said by-pass portion, a T-coupling for securing said retort to said manifold, means for conducting vapor from said retort to the engine fuel supply, and means for returning the purified lubricant from said retort to the engine oil reservoir. 115 120 125

15. In combination with an internal combustion engine, a vaporizing retort, suction means for introducing used lubricant into said retort, a collecting chamber having a circular collar for receiving purified lubri- 130

cant from said retort, an oil reservoir having a laterally extending portion provided with an opening in its upper surface, said chamber extending through said opening with said collar resting on the upper surface of said extension, and means for securing said chamber to said extension.

16. A device of the class described comprising, in combination with an internal combustion engine having an exhaust manifold, a retort secured at the upper end thereof to said manifold adapted to be heated by the exhaust gases of the engine passing through said manifold, baffles in said retort, a pipe for conducting the lubricant of the engine to said retort, a suction connection for the retort, said connection constituting a means for conducting volatile products distilled in the retort to the fuel intake of the engine, a collecting chamber positioned on the opposite side of the engine from said exhaust manifold, means for conducting purified lubricant from the retort to the collecting chamber, connecting means between said chamber and the oil reservoir of the engine, and means in said collecting chamber for intermittently discharging purified lubricant from the chamber into the reservoir.
17. In a continuous process oil rectifying system for internal combustion engines, in combination a vacuum retort having an inlet for impure oil, an outlet for rectified oil and a downwardly directed vacuum connection at the top thereof, and collecting and discharge chambers mounted independently of and at a distance from said retort and connected to said outlet, said discharge chamber being provided with automatic valve mechanism which intermittently breaks the vacuum therein and connects the chamber to the engine crank case to return the rectified oil to the crank case, said valve mechanism also closing at such time, the inlet to the discharge chamber, to preserve the vacuum in the retort.

In testimony whereof I have signed this specification.

ALFRED MOORHOUSE,
